BRANDING IRON HEATER

Herman J. Jurgens, Gurley, Nebr.

Application August 6, 1948, Serial No. 42,839

2 Claims. (Cl. 126—229)

1

This invention relates to heating stoves, and more particularly to a stove for heating branding irons for use in cattle branding operations.

A main object of the invention is to provide a novel and improved branding iron heater which is simple in construction, easy to set up and which operates very efficiently under outdoor conditions such as on the open prairie where cattle are branded.

A further object of the invention is to provide an improved branding iron heater of the portable type which operates on bottled gas, the heater being inexpensive to manufacture, and being very sturdy in construction, and providing rapid heating of branding irons to a desired temperature without overheating the irons.

Further objects and advantages of the invention will become apparent from the following description and claims, and from the accompanying drawings, wherein:

Figure 1 is a longitudinal vertical cross-sectional view taken through a branding iron heater constructed in accordance with the present invention.

Figure 2 is a top plan view, partly broken away, of the branding iron heater of Figure 1.

Figure 3 is a right end view of the branding iron heater of Figure 1.

Figure 4 is a left end view of the branding iron heater of Figure 1.

Figure 5 is a vertical transverse cross-sectional view taken on line 5—5 of Figure 2.

Referring to the drawings, 11 designates a generally rectangular sheet metal housing provided at its corners with supporting legs 12. Housing 11 has a bottom wall 13, side walls 14, 14 and the end walls shown respectively at 15 and 16. Secured in the housing is an intermediate horizontal partition wall 17, the lower edge of front end wall 15 being joined to the front edge of wall 17 to define therebelow an air intake opening 18. Secured in the lower rear portion of housing 11 is a rearwardly and upwardly inclined partition wall 19 defining with bottom wall 13 a tool compartment 20, the lower edge of rear end wall 16 being joined to the rear edge of wall 19. Designated at 21 is a hinged door for the tool compartment 20.

The forward portions of side walls 14, 14 have vertical extensions 22 defining with the front end wall 15 a heating chamber 23 which is open at its rear end. Secured to the top edges of extensions 22 is a top wall 24 having an angled closure 25 hinged to its forward edge. As shown in Figure 1, a plurality of horn branding irons 26 may

be inserted between closure 25 and the top edge of forward end wall 15 with the ends of the irons supported in the heating chamber 23. The upper inner surface of wall 15 and the bottom surface of wall 24 are lined with suitable refractory heat insulating material as shown at 27.

Secured transversely in the rear portion of heating chamber 23 is a depending forwardly inclined baffle plate 28 having a horizontal rearwardly extending top flange 29. Designated at 30 is a transverse vertical wall plate secured in the housing 11 below and rearwardly of baffle plate 28. Designated at 31 is a forwardly flaring fuel-mixing conduit provided at its forward end with a manifold portion 31', secured in plate 30 and provided at its rear end with an adjustable conventional air-mixing valve 32 which admits air into conduit 31 in a conventional manner. Connected to the mixing valve 32 is the fuel supply pipe 33 which extends through rear wall 16 and is provided with a suitable regulating valve 34. The rear portion of partition wall 17 is formed with a plurality of apertures 35 allowing air to enter the space behind mixing valve 32. Pipe 33 carries a baffle disc 36 rearwardly spaced from mixing valve 32.

Connected to the manifold 31' at the forward end of mixing conduit 31 is a transverse branched conduit 37 to which are connected a plurality of spaced burners 38. The top margins of side walls 14, 14 are outwardly flanged, as shown at 39, 39 and slidably engaged therewith are the channelled side margins 40, 40 of the top cover 41. Secured to the forward end portion of top cover 41 are a plurality of upstanding spaced tab members 42 defining vertical slots therebetween for receiving the branding irons 43. Secured to the rearward portion of the cover 41 is a transverse angle bar 44 which serves as a rear support for the irons 43, as shown in Figure 1. The forward support for the irons is the transverse horizontal flange 29.

The rear margin of cover 41 is downwardly flanged, as shown at 45, cooperating with a top flange 46 on end wall 16 to limit forward movement of top cover 41 to the position shown in Figure 1. In this position the guide tabs 42 are positioned just behind the horizontal transverse flange 29.

Pipe 33 is connected through valve 34 and a nipple 47 to a suitable fuel source such as a gas bottle. When valve 34 is open, gas flows into mixing valve 32 and mixes with air flowing into the space adjacent valve 32 through the apertures 35. The fuel mixture flows through the

expanding conduit 31 to the burners 38 and is ignited at said burners. Additional air for combustion enters the heating chamber 23 through the passage defined by baffle plates 30 and 28.

As shown in Figure 1, the regular branding irons 43 and the horn branding irons 26 are supported with their marking ends positioned above the burners 38, whereby the ends of the irons are heated uniformly and in an efficient manner. The irons may be readily removed from the heater for use and may be readily returned thereto for reheating.

Secured rigidly to the rear end wall of the housing is a wire brush 48 which is employed for cleaning the ends of the branding irons whenever required.

While a specific embodiment of a heater for cattle branding irons has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A heater for cattle branding irons comprising a housing, a horizontal partition in said housing defining upper and lower spaces therein, the front end of the lower space being open and the rear portion of the partition being apertured to allow air to enter the rear portion of the upper space, a gas burner in the forward portion of the upper space, a mixing conduit connected to the burner and extending rearwardly in said upper space, said conduit including an air admission valve at its rear portion, means for connecting the rear end of the conduit to a source of gas fuel, a top cover detachably secured to said housing, the forward portion of the housing being extended vertically to define a hood opening rearwardly over said top cover and overlying said burner, spaced tabs on said top cover defining slots therebetween for receiving branding irons

with their ends positioned within the hood, and a transverse hinged closure at the top forward corner of said hood for admitting additional branding irons within the hood, said closure having a depending outer marginal portion engageable with the said additional branding irons.

5 2. A heater for cattle branding irons, comprising a generally rectangular housing, a horizontal partition in said housing defining upper and lower spaces therein, the front end of the lower space being open and the rear portion of the partition being apertured to allow air to enter the rear portion of the upper space, a gas burner in the forward portion of the upper space, upper and lower spaced transverse baffle plates in the upper space rearwardly adjacent the burner, a mixing conduit connected to the burner and extending rearwardly through the lower baffle plate, said conduit including an air admission valve at its rear portion, means for connecting the conduit to a source of gas fuel, a top cover detachably secured to said housing, the forward portion of the housing being vertically extended to define a hood opening rearwardly over said top cover, transversely spaced tabs on said top cover defining slots therebetween for receiving branding irons with their ends positioned within the hood, and a transverse hinged closure at the top forward corner of said hood for admitting additional branding irons within the hood.
